UNITED STATES PATENT OFFICE

135,610

DESIGN FOR A CRUCIFIX OR SIMILAR ARTICLE

James P. Calnan, Belmont, Mass.

Application January 14, 1942, Serial No. 105,204

Term of patent 14 years

To all whom it may concern:

Be it known that I, James P. Calnan, a citizen of the United States, residing at Belmont, in the county of Middlesex and State of Massachusetts, have invented a new, original, and ornamental Design for a Crucifix or Similar Article, of whom the following is a specification, reference being had to the accompanying drawing, forming part thereof.

In the drawing,

Fig. 1 is a front elevational view of a crucifix showing my new design; and

Figs. 2, 3, 4, 5, and 6 are enlarged sectional views taken on lines 2—2, 3—3, 4—4, 5—5 and 6—6, respectively, of Fig. 1.

The dominant feature of the design resides in the provision of jewels or faceted jewel-like inserts in the hands, feet, breast, and forehead of the figure shown on the crucifix, at the points indicated by the sectional views of the drawing, so that the inserts in the hands, feet, and breast represent the traditional wounds in the body of Christ and the inserts across the forehead represent the crown of thorns.

I claim:

The ornamental design for a crucifix or similar article, substantially as shown and described.

JAMES P. CALNAN.
